DESIGN.

I. T. MONTROSS.
HEATING STOVE.

No. 16,793.

Patented July 13, 1886.

Wm. J. F. Engleby
D. Ferguson.

Inventor.
Isaac T. Montrof

UNITED STATES PATENT OFFICE.

ISAAC T. MONTROSS, OF PEEKSKILL, NEW YORK.

DESIGN FOR A HEATING-STOVE.

SPECIFICATION forming part of Design No. 16,793, dated July 13, 1886.

Application filed May 18, 1886. Serial No. 202,579. Term of patent 7 years.

To all whom it may concern:

Be it known that I, ISAAC T. MONTROSS, a citizen of the United States, residing at Peekskill, in the county of Westchester and State 5 of New York, have invented and produced a new and original Design for a Stove, of which the following is a specification, reference being had to the accompanying photograph, forming part thereof, which fully illustrates my design.

10 The legs of my stove, with their uniting plates *d*, form a square frame, and the several parts are profusely ornamented with flat relief scroll-work and margins, as illustrated. Upon this frame the base-plate *B* rests, having its edges 15 slightly beveled with a curved droop, the beveled edge bearing a scroll ornamentation, as shown at *a'*. The ash-box *C* rises perpendicularly from the base-plate *B*, and is rectangular in plan, being foreshortened and exposing the 20 hearth-like surface *e* on plate *B*. The corners are rounded in the needed form, as shown at 1. The front is provided with a door, 2, which is hinged at *f f*, and has a catch, *c*, and knob *c'*. This door has an edge of molding, *c''*, in relief, 25 within which are vertical rectangular openings 3 3 3, for the purpose of a draft-register, which is operated by the knob 4. A small beaded molding skirts the edges of the openings 3 3 3. Upon the surface of the door are ornamental 30 scrolls *b*, as shown, the said scroll crossing and recrossing the openings 3 3 3, not having any of its parts cut away to accommodate said openings, yet being sufficiently delicate not to interfere with a proper draft-opening. The two 35 sides of the ash-box are finished in a manner similar to the side *f*, as shown, each side containing a relief-molding, *b*, forming a panel inclosing an ornamental scroll, *g*. Brackets, as at *h h*, spring from each side of the ash-box 40 and support foot-rests, as at *j*, the rests terminating in knobs *g g*. The brackets and rests bear ornamentation, as shown. The ash-box is surmounted by the plate *D*, having a liberal ovolو margin, *a''*, ornamented with a scroll 45 tracery, as shown. On the front edge said margin is adapted to receive a name-plate, *k*.

The main body of the stove *E* is rectangular in plan, except that the front and sides for the width and extending to the height of the door-spaces have an outward swell, as shown, the profile of which in the plan is convex at its

outer points and concave where it joins the plane surfaces. One of the long sides of the rectangle forms the front, and the other, of course, the back, of the body *E*. The said body 55 being thus narrower from front to back than from side to side, and being placed with the back against the rearmost line of the plain surface of the plate *D*, leaves a hearth-like surface, *m*, on the plate *D*. Upon the sides it 60 will be observed that their convexity encroaches upon the ornamental edge of plate *D*, as shown at *l*.

The plates forming the front *F* and sides *G* represent vertical fluted columns *o o o o*, united 65 by cross-bands *p p p p*, similarly fluted, the reed-bands *q q*, and hatched bands *r r* at the top, the intersections of the vertical and cross bands being relieved by the rosettes *s s s*. The top bands, *r r*, are not curved as the lower 70 ones, but are straight, and the paneled stipple ornamentation *t* is likewise on a flat surface. The dome-like sections *u u* conform at their bottom horizontal edges to the curve outward 75 of the reed-bands *q*, upon which they rest, arching upward and over to the flat surface *t*.

The clinker-doors *I I* are skeleton in form, consisting of the molded frame *v* and the scroll *v'*. The fire-doors *J J* harmonize in shape with the clinker-doors, the ornamental scrolls differing, as will be seen in the illustration, and having cross-rails beneath the scroll, one centrally horizontal, as at *o''*, and two vertical, as *z z*, dividing the illuminated space into six lights. These doors are provided on the inside 85 with the usual mica-holding frames. Catches and knobs for all these doors are provided, as shown at 10 10 10 10.

The body *E* is surmounted by a top, *K*, consisting of two curved inwardly-sloping surfaces, 90 11 and 12, rising in pyramidal form to a plain square, flat, top, 13. The slopes are of an ovolو form, the first being narrower and of a sharper curve than the second one, and projecting its full width over all sides of the 95 stove. The scroll ornamentation on the slope 11 is similar in design to that on plates *B* and *D*. That on the second slope, 12, is in harmony with that on the dome-like sections *u u*.

The flat top 13 is pierced with an opening to 100 the coal-magazine within the stove, and is covered with the crowning-plate *L*, which com-

plete the pyramidal form of the stove-top. The ornamentation of this plate is in keeping with that on the slope 12. The top is surmounted by a neat vase or urn, substantially as represented.

Upon each corner of the body of the stove are placed semicircular columnar pieces *y*, ornamented as shown, and provided with the capital finish *z*.

11c The rear side of the stove has a flue-extension, 14, from the bottom of the ash-box to the beginning of the swell 16, at which point it curves outward in the manner shown, terminating in the top 17.

115 Having described my design, what I claim, and wish to secure by Letters Patent, is—

1. The design for a stove herein shown and described, the same consisting of the configuration and ornamentation of the several

parts—namely, the top *L* and *K*, surmounted by an urn, the body *B*, with corner-plates *y*, ash and clinker doors, and having convex front and sides, the convexity terminating at the top in the dome-sections *u*, plate *D*, with hearth *m*, and curved drooping edge *a'*, ash-box *C*, with paneled sides, ash-door in front, and foot-rests on the sides, plate *B*, with hearth *e* and beveled margin *a*, and the base *A*.

2. In a design for a stove, a door consisting of the molded frame, leaf-scroll ornamentation, and cross-rails, as herein shown and described.

3. In a design for a stove, corner columnar plates *y*, bearing scroll tracery and having scalloped capitals *z*, as herein shown and described.

ISAAC T. MONTROSS.
